UNITED STATES PATENT OFFICE

RALPH E. FERRIS, OF SWISSVALE, PENNSYLVANIA, ASSIGNOR TO WESTINGHOUSE ELECTRIC & MANUFACTURING COMPANY, A CORPORATION OF PENNSYLVANIA

INSULATED COLLECTOR

Application filed May 31, 1927. Serial No. 185,395.

My invention relates to current-collecting devices for dynamo-electric machines.

Heretofore, in making collector rings, it has been customary to provide either a base 5 of insulating material in which the collector rings were embedded or a plurality of concentric sleeves of insulating material over which the collector rings were forced.

With the former method, it has been found 10 that the body of the insulating material did not have sufficient mechanical strength to withstand the forces incident to operation. With the latter method, considerable difficulty has been encountered in assembling 15 the concentric sleeves of insulating material, since it has been necessary to provide sleeves of very exact dimensions in order that they may fit tightly together.

Furthermore, when utilizing the concentric 20 sleeves mentioned above, it was necessary to insert the connectors or terminals in the sleeves of insulating material before the collector rings were forced on. The connections between the terminals and the collector rings 25 were made after the collector rings had been forced on, so that the electrical connection between the two members was often quite imperfect.

One of the objects of my invention is to 30 provide a current-collecting device which is rigid in construction and relatively easy to assemble.

Another object of my invention is to provide a current-collecting device in which the 35 terminals and collector rings may be connected before the device is assembled.

A further object of my invention is to provide a current-collecting device which will 40 have a body of rigid material which may be forced on a machine shaft after the device is assembled.

In the accompanying drawing, Fig. 1 is a 45 longitudinal sectional view of a current-collecting device embodying my invention.

Fig. 2 is a view, in end elevation, of the structure illustrated in Fig. 1, and

Fig. 3 is a fragmentary view, showing a 50 transverse section taken on the line III-III of Fig. 1.

In the embodiment of my invention shown

in the accompanying drawing, a hollow cylindrical body member or bushing 1 of steel is wrapped with a plurality of layers 2 and 3 of flexible mica. Three collector rings, 4, 5 and 6, of good-conducting material, arranged to fit the mica-wrapped bushing 1, are shrunk thereon and spaced at equal longitudinal intervals.

The left-hand collector ring 4 has an oblong slot or groove 7 extending longitudinally across its under side. One end 8 of a flat terminal 9 of good-conducting material is disposed in the slot 7 and secured to the collector ring 4 by any suitable means, such as welding or soldering. The terminal 9 is 60 encased in a flat tubular member 11 of insulating material and is disposed longitudinally along the smooth outer periphery of the wrapped bushing 1.

The middle collector ring 5 is similar to the one described above, except that it has two slots or notches 12 and 13 spaced 120° apart around its inner periphery. One of the slots 12 is similar to the single slot 7 of the left-hand collector ring and serves to 70 connect with a terminal strip 14. The other slot 13 is somewhat larger and is arranged to admit the insulated portion 11 of the flat terminal 9, which is attached to the left-hand collector ring 4.

A third collector ring 6, similar to the second ring 5, and having, in addition, a second large slot 15, is disposed at the right-hand end of the bushing. The three slots in this collector ring are disposed at equal distances 75 around the inner periphery of the ring.

A third flat terminal 16, similar to those described above, is secured in the small slot in this collector ring. The right-hand collector ring 6 is disposed upon the bushing 1 in such 80 position that the flat terminals connected to the middle ring and the left-hand ring will extend through the two larger slots.

A quantity of asphaltic cement 17 is disposed around the tubular members 11 enclosing the terminals, thereby providing additional protection against grease and dirt and, in addition, providing a relatively smooth surface which may be easily wiped clean of dirt and grease or any other material tending to 85 100

provide a short-circuit path between adjacent collector rings.

In assembling my device, the terminals are each joined to their respective collector rings. The tubular insulating members, which have been shaped to fit over the terminals, are then slipped over the latter. Finally the collector rings are heated and forced on the bushing which has previously been wrapped with sheets of flexible mica. When the rings cool, they contract and are held securely in position and also maintain the terminals in their proper positions.

By my invention, I provide a current-collecting device which is simple and rugged and easy to assemble. In addition, I am able to connect the terminals and rings before the device is assembled.

I claim as my invention:

1. A collector-ring assembly comprising a cylindrical metallic supporting member, a substantially smooth insulating material therearound, and a plurality of slip rings disposed, in spaced relation, on said insulating material in tight, frictional engagement therewith, each of said slip rings having a flat terminal member secured thereto, said terminal members being enclosed in individual tubular insulating members and extending longitudinally alongside the flat outer surface of said layer of insulating material, some of said slip rings being grooved in their under surfaces to receive the tubular insulating member of a terminal of another slip ring, the junction between each ring and its terminal member being of a type requiring no more space, in the radial direction, than the thickness of said terminal member with its tubular insulating enclosure in place.

2. A collector-ring assembly comprising a cylindrical metallic supporting member, a substantially smooth insulating material therearound, and a plurality of slip rings disposed, in spaced relation, on said layer of insulating material in tight, frictional engagement therewith, each of said slip rings having a flat terminal member secured thereto, said terminal members being enclosed in individual tubular insulating members and extending longitudinally alongside the flat outer surface of said layer of insulating material, some of said slip rings being grooved in their under surfaces to receive the tubular insulating member of a terminal of another slip ring, and a body of insulating material disposed over said terminal members and providing a smooth outer surface.

3. A collector-ring assembly comprising a cylindrical metallic supporting member, a substantially smooth insulating material therearound, and a plurality of slip rings disposed, in spaced relation, on said insulating material in tight, frictional engagement therewith, each of said slip rings having a flat-bottomed groove in the inner periphery

thereof and a flat terminal member secured in good electrical contact to said flat bottom of said groove by means independent of said tight, frictional engagement between the inner peripheries of the rings and the smooth cylindrical supporting surface, said terminal members being enclosed in individual tubular insulating members and extending longitudinally alongside the flat outer surface of said layer of insulating material, some of said slip rings being grooved in their under surfaces to receive the tubular insulating member of a terminal of another slip ring, the junction between each ring and its terminal member requiring a radial depth at least as small as the depth of said last-mentioned grooves.

4. A collector-ring assembly comprising a cylindrical metallic supporting member, a substantially smooth insulating material therearound, and a plurality of slip rings disposed, in spaced relation, on said insulating material in tight, frictional engagement therewith, each of said slip rings having a flat-bottomed groove in the inner periphery thereof and a flat terminal member molecularly integrally joined to said flat bottom of said groove, said terminal members being enclosed in individual tubular insulating members and extending longitudinally alongside the flat outer surface of said layer of insulating material, some of said slip rings being grooved in their under surfaces to receive the tubular insulating member of a terminal of another slip ring, the junction between each ring and its terminal member requiring a radial depth at least as small as the depth of said last-mentioned grooves.

In testimony whereof, I have hereunto subscribed my name this 25th day of May, 1927.

RALPH E. FERRIS.
